SAFETY CONTROL FOR A CUTTING MACHINE CLAMPING DEVICE

Joseph C. Doty and Robert J. Buchwalder, Dayton, Ohio, assignors to Harris-Intertype Corporation, Dayton, Ohio, a corporation of Delaware

Filed June 17, 1959, Ser. No. 820,944

2 Claims. (Cl. 269—23)

This application relates to cutting machines for cutting stacks of paper or for cutting other sheet material, and particularly to an improved safety control for the clamp on such machines which retains the material stationary during the cutting stroke.

In guillotine type cutters, for example of the type shown in Spiller et al. Patent 2,599,591, issued June 10, 1952, it is customary to provide a pressure operated clamping device adjacent to the cutting knife, and operable to clamp the sheet material to be cut against the top surface of the cutter table. The forces exerted by such clamps may be considerably high, capable of injuring the operator if he inadvertently places his hands under the clamp, or if the clamp accidentally operates while he is reaching underneath it to arrange material on the table. Therefore, it is desirable to provide a safety control circuit which requires deliberate positive action by the operator to cause clamping movement.

Normally, the clamping operation is under control of a foot operated bar which extends approximately within a vertical plane containing the front edge of the table, and operating to swing about a hinge axis located under the table, behind the main or foot-engaging cross piece of the bar. To assure that this bar is not accidentally engaged by the operator, while he is moving about the front of the machine as in positioning a pile of material to be cut, and while his hands are in the danger zone beneath the clamp, it is customary to provide a locking device for the clamp operating bar which must be engaged by one hand before the bar will be effective to operate the clamp.

The net effect of such an arrangement is to leave the operator with one hand free to maneuver the pile while his other hand operates the locking device and a foot operates the bar to produce lowering of the clamp. The safety feature, therefore, is attained from the requirement that only deliberate action by the operator will lower the clamp. Strictly speaking, the operator still is able to move his free hand into the danger zone beneath the clamp, but he is warned by his required deliberate movements, and the clamp cannot be lowered accidentally without such deliberate procedure.

The present invention provides an improved, simplified safety control for clamp operation which still requires deliberate positive action by the operator to lower the clamp, and which is safe from accidental operation, but which frees both hands of the operator for adjustment of the pile, if desired, as the clamp descends. This improved control is operated by a foot treadle, or the like, which is so located, and so hinged, that the operator must place his foot in an unusual position, and move the foot in a manner which is somewhat abnormal from a standing position.

The primary object of this invention, therefore, is to provide an improved safety control for the clamp of cutting machines, wherein lowering or clamping movement of the clamp under power is controlled by a foot operated treadle member which is supported well beneath the cutter table, such that the operator must reach his foot under the table to engage the treadle, and wherein the treadle is pivotally mounted adjacent its edge closest to the operator such that the operator must press downwardly and forwardly with his foot, moving the

2

treadle from its normally inclined position toward a horizontal position, to produce powered lowering of the clamp.

Other objects and advantages of the invention will be apparent from the following description, the accompanying drawing and the appended claims.

In the drawing:

FIG. 1 is a side view of a cutting machine, shown partially in dotted outline, incorporating the clamp control arrangement provided by this invention;

FIG. 2 is a partially broken front view of the cutting machine shown in FIG. 1, with the knife and clamp structure, including the clamp drive shown schematically, and with the housing of the machine shown in dotted outline;

FIG. 3 is a side view on an enlarged scale, showing details of the treadle construction and its mounting; and

FIG. 4 is a plan view of the clamp control treadle.

Referring to the drawing, which shows a preferred embodiment of the present invention, a cutting machine of the type with which the invention is concerned is shown in dotted outline as including a cutting table 10 having a forwardly projecting portion terminating in a front edge 12 (FIG. 1). A guillotine type cutting knife

15 is mounted for reciprocating movement in a generally vertical plane toward and away from the surface of table 10, to cut material, for example a stack of sheets of paper, supported thereon. Immediately behind the knife

15 is a power operated clamp 18 which also is mounted for vertically reciprocating movement, under the control of draw bars 20 connected to opposite sides thereof. Each of the draw bars is fastened at its lower end through a hinge joint 22 to a connecting rod 23 which in turn is pivotally secured to one end of a bell crank 25 mounted to pivot in a generally vertical plane therebeneath. The two bell cranks 25 are joined by a tie rod 28 for movement in unison, and the power to move the clamp 18 is provided by a double-acting hydraulic motor 30 of the piston-cylinder type which has its piston rod 32 extended and pivotally connected to one of the bell cranks 25, as shown in FIG. 2.

Control of the motor 30 may be provided by any suitable hydraulic control system, for example of the type described and illustrated in the aforementioned Patent 2,599,591. Thus, the directional control valve 33 for the motor 30 will govern raising and lowering of clamp 18, and movement of this valve is in turn controlled by an operating cable 35 which is fastened at one end to a yoke piece 37.

The control of cable movement is provided by a foot operated treadle indicated by the general reference numeral 40, and including mounting brackets 42 which are bolted to the base 43 of the machine, and to which are secured the stationary plates 44 of conventional spring hinges 45. These hinges are of the well-known type which incorporate therein torsion springs acting to bias the relatively movable plates of the hinge in a desired direction.

In the particular arrangement shown herein the movable hinge plate 47 is bolted to the treadle plate 50 and the torsion springs are arranged to urge the treadle plate into a normally raised position, i.e. biased in a counter-clockwise direction as viewed in FIG. 3. Stop tabs 52 extend from the forward ends of mounting brackets 42 and engage the under surface of the forward edge of treadle plate 50 to limit the movement of the treadle plate under the spring hinge bias. An arm 55 is bolted to the normally upper or lowermost end of treadle plate

50 and is pivotally connected to the cable yoke 37 through a hinge pin 57.

With reference to FIGS. 1 and 3, it will be noted that the hinge axis about which the treadle plate 50 swings

is located at 60, the center line of the hinges 45, and this axis is substantially at the forward or lowermost edge of the treadle plate, although spaced somewhat rearwardly of the extreme forward edge of plate 50. Thus in the normal or at rest position the treadle plate is biased to extend in a plane projecting upwardly and rearwardly with reference to the front of the cutting machine, and the operator must place his foot upon the treadle plate and press downward and inward, with reference to the base of the machine, to actuate the clamp control valve 33.

Furthermore, the extreme forward edge of treadle plate 50, and therefore its hinge axis, is located beneath and rearwardly of the front of table 10, within, with reference to the machine base, an area bounded by a vertical plane extending through the forward edge of table 10, as indicated by the dot dash line 62 in FIG. 1. The operator station is normally in front of table 10, outside of the area bounded by this plane, where the spaced apart operating levers 65 for controlling the knife's cutting cycle are mounted. Thus the operator, standing in front of the plane 62, must deliberately place his foot within the area underneath the table to engage the treadle plate 50 and operate the clamp. During normal movement about the front of the machine the operator will not normally place his foot within this area, and even if this should happen accidentally, he would engage the extreme forward end of treadle 50 and would tend to move that plate in a direction the same as the bias of spring hinges 45, or against the stops 52. Thus, even if he should accidentally engage the treadle plate no movement of the clamp will occur since the treadle will not be depressed in a direction to move the operating cable 35.

While the form of apparatus herein described constitutes a preferred embodiment of the invention, it is to be understood that this invention is not limited to this precise form of apparatus and that changes may be made therein without departing from the scope of the invention which is defined in the appended claims.

What is claimed is:

1. A safety control construction for a machine having a horizontal work table mounted on a base, a power

driven clamp member arranged to clamp material in predetermined position on the top of said table, and selectively operable drive means for said clamp member; said safety construction comprising means on said table forming a work station at one edge of said table top in fixed relation to said clamp member, a foot operated treadle supported from said base below said table top and substantially inwardly beneath said table top from a vertical plane through one said edge of said table top at said work station, pivot means connected to said treadle adjacent the edge thereof closest to said vertical plane, biasing means cooperating with said pivot means supporting said treadle in a normal position with the surface thereof extending in an inclined plane directed upwardly and rearwardly with respect to said work station, said work station being in such spaced relation to said pivot means that an operator is required to stand at said work station to control said machine and in such standing position is required to extend one foot in a deliberate and abnormal manner beyond said station and underneath said table top to place such one foot in operative position on said treadle, and means connecting said treadle to said selectively operable drive means for producing a lowering movement of said clamp member in response to pivotal motion of said treadle against said biasing means from its said normally inclined position down and away from said work station toward a horizontal position and continued holding of said treadle away from its said normally inclined position.

2. In a machine as defined in claim 1, stop means mounted adjacent said treadle and located outwardly of said pivot means toward said work station and said vertical plane, said stop means engaging the lowermost edge of said treadle forwardly of said pivot means.
